(57) **CLAIM**

The ornamental design for a razor, as shown and described.

DESCRIPTION

FIG. 1 is a top, front, right side perspective view of a razor, showing my new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1; and,

FIG. 10 is an enlarged view of a portion labelled 10 in FIG. 2.

The dash dot dash lines in FIG. 1, FIG. 2, FIG. 9 and FIG. 10 are for the purpose of depicting the cut line of the enlarged view and form no part of the claim.

1 Claim, 10 Drawing Sheets
